NEEDLE

Walter J. Schulz, San Leandro, Calif.

Application May 31, 1945, Serial No. 596,941

1 Claim. (Cl. 112—222)

(Granted under the act of March 3, 1883, as
amended April 30, 1928; 370 O. G. 757)**1**

This invention relates to needles and more particularly to sewing machine needles.

Although sewing machine needles previously have been provided with longitudinal grooves for receiving and guiding thread to the eyes of the needles, such construction does not prevent the material being sewn from entering the grooves or the thread from slipping out of said grooves. Upon the downstroke of a needle of this type, the thread, being under tension, is frictionally engaged by the material being sewn so as to fray and weaken said thread. When the needle moves upwardly, the thread is slack and has a tendency to slip or "pop" out of the longitudinal groove away from the shuttle of the sewing machine, whereby said shuttle fails to pick up said thread and the machine "skips a stitch."

An object of the invention is, therefore, to provide an improved sewing machine needle of such construction as to prevent the thread from contacting the material being sewn prior to passing through the eye of the needle so as to eliminate friction between said thread and material and to confine the thread so as to assure the same being picked up by the shuttle of the sewing machine.

Other objects of the invention are to provide for receiving and directing thread to the eye of the needle and for confining the thread in the opening to shield the same against frictional engagement with the material being sewn prior to passing through said eye; to provide confining means functioning to direct the slack of the thread toward the shuttle of the sewing machine to assure said shuttle picking up said thread and thereby prevent said machine from "skipping a stitch"; to provide confining means made integral with the body of the needle so as to form a longitudinal passage in said body with a transverse slot for receiving and directing said thread; to provide a longitudinal thread directing groove and a semi-cylindrical shield frictionally engaging around the body of the needle and overlying the intermediate portion of the groove to form a passage for confining the thread and preventing the same from contacting the material being sewn prior to said thread passing through the eye of the needle; to provide improved elements and arrangements thereof in a sewing machine needle of the character described; and to carry out the noted objects in a facile, economical and efficient manner.

In accomplishing these and other objects of the present invention, I have provided improved details of structure, the preferred form of which is

2

illustrated in the accompanying drawing, wherein:

Fig. 1 is an enlarged, longitudinal, sectional view of a sewing machine needle embodying the features of the present invention.

Fig. 2 is an enlarged, elevational view of a modified form of needle.

Fig. 3 is a horizontal, cross-sectional view, taken on the line 3—3 of Fig. 2.

- 10 In Fig. 1, the numeral 1 designates the cylindrical body of a sewing machine needle having a tapered, pointed lower end 2. A cylindrical eye 3 extends diametrically through the body 1 immediately above its pointed end 2 for receiving thread T and passing or forcing the same through the material to be sewn, which material is indicated by the broken lines M. The outer ends of the eye 3 are preferably enlarged or flared so as to provide bevelled recesses 4 below and communicating with said eye. In order to accommodate the thread T upon the downstroke of the needle body through the material M, a short, longitudinal groove or recess 5 is formed in the exterior surface of said body above the eye and in vertical alignment with the longitudinal axis of said eye. The lower end of the recess 5 communicates with the left-hand end of the eye so as to receive the thread directly from said eye and reduce the frictional engagement between the material and said thread upon the needle body passing through said material. It is preferable to taper or bevel the upper end of the recess as shown by the numeral 6 and said recess is preferably semi-cylindrical.
- 20 For receiving and directing the thread to the eye 3, a longitudinal, cylindrical passage or bore 7 is formed in the body in vertical alignment with the longitudinal axis of said eye and has its lower end communicating with the right-hand end portion of the eye. Although not essential, the bore 7 is illustrated as extending entirely through the body from the eye to the upper end of said body so that the main portion of the latter is hollow or tubular. A short, longitudinal opening or slot 8 is formed in the body in communication with the upper region of the bore 7 to provide an inlet for directing the thread to said bore. The upper and lower ends of the slot 8 are preferably bevelled or rounded off as shown by the numeral 9 and said slot is disposed in the same vertical plane with but diametrically opposed to the recess 5 so as to be vertically aligned with the longitudinal axis of the eye 3. It is preferable to bevel or round off the lower extremity of the body portion between the recess

and bore as shown by the numeral 10. The beveling or rounding off of the areas 9 and 10 prevents the abrasion or cutting of the thread by what might otherwise be sharp edges.

Operation

The operation of a sewing machine needle constructed as described herein is as follows:

The needle is threaded by inserting the thread T into the slot 8 and feeding the same downwardly through the bore 7 of the body 1 to the eye 3. From the eye, the thread is passed outwardly through the left-hand end of said eye below the recess 5 and a sufficient length of thread is drawn through the needle body to assure the same being picked up by the shuttle (not shown) of the sewing machine upon reciprocation of said body and actuation of said shuttle.

Upon securing or stitching the free end portion of the thread, the downstroke of the needle body through the material M draws or forces said thread downwardly therewith so as to cause feeding movement of the thread relative to said body. The travel of the thread is approximately double the length of the downstroke and at substantially twice the speed, whereby said thread is under tension during said downstroke. The thread is shielded against contact with the material prior to passing through the eye 3, due to the provision of the bore 7 and inlet slot 8, in order to minimize frictional resistance to such movement of said thread. The stitched end portion of the thread engages within the recess 5 upon the downstroke of the needle body so as to further eliminate binding of said thread between the material and said body.

During the upward reciprocation of the needle body, the tension upon the thread is removed and sufficient slack is provided beneath the material to form a loop L which is picked up by the shuttle of the sewing machine so as to form a stitch. Since the thread is confined within the bore 7, the loop L is formed to the left of the needle body and there is no tendency for the slack and said loop to be displaced to the right of said body beyond the reach of the shuttle. Subsequent reciprocation of the needle body and travel of the thread occurs with minimum friction and proper positioning the thread loop.

Due to the aforesaid construction which reduces drag or wear upon the thread to a minimum, fraying of said thread is substantially eliminated. Undesirable tension upon the thread is removed by the shielding of said thread prior to its passage through the eye of the needle body so as to facilitate travel or movement of the thread relative to said body. Since the bore 7 extends through the upper end of the needle body, said body may be used as a hollow needle in sewing machines in which the thread is fed downwardly through the needle bar (not shown).

Modified form

Substantially comparable results may be obtained by the modified construction shown in Figs. 2 and 3, wherein a conventional needle body 11 is illustrated. The body has a pointed lower end 12 with a diametric eye 13, having flared or enlarged end portions 14. A groove or recess 15, similar to the recess 5, extends longitudinally upwardly

from one end of the eye 13, while an elongate channel or groove 16 is disposed diametrically of the recess above and in communication with the opposite end of said eye. It is preferable to bevel or taper the upper ends of the recess 15 and groove 16 as shown by the numerals 17 and 18, respectively.

In order to confine the thread T within the groove 16 and direct the same to the eye 13 without frictionally contacting the material M, a semi-cylindrical plate or shield 19 is adapted to frictionally engage around the body 11 for enclosing the major portion of said groove. The shield 19 is formed of thin metal, or other suitable material, and is of less length than the groove so as leave the eye and the upper extremity of said groove exposed. Due to this relationship, the thread is freely fed or directed to the eye through the groove without contacting the material upon the downstroke of the body through said material and the thread loop L is properly disposed upon subsequent upward movement of said body. In order to reduce frictional resistance to the passage of the shield through the material, it is preferable to feather the marginal edges of said shield as shown by the numeral 20 (Fig. 3).

While I have shown certain embodiments of my invention, it is apparent that the device is susceptible to further modification without departing from the spirit of the invention. I do not wish, therefore, to be limited by the disclosures set forth, but only by the scope of the appended claim.

The invention described herein may be manufactured and used by or for the Government of the United States of America for governmental purposes without the payment of any royalties thereon or therefor.

I claim:

A sewing machine needle including, a cylindrical body having a tapered pointed end, the body having a diametric eye above its pointed end for receiving thread, said body having a longitudinal bore formed therein above the eye with its lower end communicating with said eye adjacent one end thereof, the body having an opening extending radially outward through the wall of the upper portion of said bore, whereby the thread may be directed to the eye through the opening and bore so as to be shielded against the frictional engagement with the material being sewn, said body having an elongate longitudinal recess formed therein diametrically opposed to said bore, said recess lying above said eye and in communication with the other end thereof for receiving said thread therefrom to reduce frictional engagement of the thread with said material.
